UNITED STATES PATENT OFFICE.

GABRIEL A. BOBRICK, OF LOS ANGELES, CALIFORNIA.

LIQUID-SOAP DISPENSER.

1,158,166.

Specification of Letters Patent. Patented Oct. 26, 1915.

Application filed March 2, 1912. Serial No. 681,269.

To all whom it may concern:

Be it known that I, GABRIEL A. BOBRICK, a citizen of the United States, residing at Los Angeles, in the county of Los Angeles 5 and State of California, have invented a new and useful Liquid-Soap Dispenser, of which the following is a specification.

This invention relates to apparatus for dispensing measured quantities of liquid soap from a chamber or cylinder by force exerted upon a piston, and is particularly adapted for use in public places, such for instance as lavatories of sleeping cars, hotels, school buildings, etc., where a series of wash 10 basins are arranged in proximity to each other, and where the fixtures are to be used by the public.

The invention also comprises features, combinations and parts capable of use for 15 individual wash basins or at other places where it may be desired to dispense liquid soap.

The use of solid soap in public lavatories is subject to many serious objections, among 20 which may be mentioned, loss occasioned by thievery, by misplacement, and by failure to completely use the cakes; and a sense of uncleanliness and unsanitariness arising from successive using of the same cake by persons 25 who are strangers to each other and liable to transmit infection.

A difficulty to be overcome in the use of 30 liquid soap dispensers is the sense of unsanitary conditions which results from any construction of the dispensing device which 35 facilitates, induces, compels or allows the hand of the user to come into direct contact with the liquid dispensing nozzle in the ordinary operation of obtaining a charge of 40 the saponaceous liquid. Furthermore the fixtures as heretofore applied present large surfaces liable to catch the splash of soap-suds and to become untidy in appearance 45 and to be difficult to clean on account of numerous crevices and corners; and are in the way and are liable to breakage.

It is found that liquid soap dispensers 50 which are so constructed as to result in causing the dispensing device to become soapy in the course of ordinary use, are repulsive or obnoxious to many would-be users, so that the device is excluded from many public lavatories. It is also desirable that the operation of obtaining a charge of the liquid

soap should only require the use of the hand 55 that is to receive the charge.

A further reason militating against the introduction of liquid soap dispensers in public lavatories such as those maintained in Pullman cars, is the attention demanded of 60 the porter in order to keep the dispensers properly supplied with the saponaceous liquid, it being found that the several charges of soap in the separate dispensing devices become exhausted at various times, 65 thus requiring an unwarrantable amount of time and attention of the porter to keep the apparatus in running order, and also that the porter is apt to receive a call from the occupants of the car while the dispensing 70 device is dismantled preparatory to or during the operation of refilling, thus making it necessary for him to leave the dispenser dismantled at inopportune times.

An object of this invention is to provide 75 a novel dispensing fixture applicable to railway train service and elsewhere, whereby the use of liquid soap in all such places may be made practical and popular, thus doing away in such places with the great waste 80 now occasioned by the general use of solid soap in public lavatories and also avoiding the sense of unsanitary conditions and liability to infection which are at present involved in the use of soap in public lavatories. 85

Further objects are to avoid dripping of the liquid from the dispensing nozzle; to avoid any possibility of a continuous opening from the reservoir to the nozzle; to insure the delivery of a determined charge at 90 each full operation of the plunger; and to accomplish all of these objects with a neat, attractive and unobtrusive appliance of a few cheap and simple parts that are easy to 95 manufacture and assemble and difficult to be dismantled by a person not specially prepared for the work.

By placing a main supply tank in the baggage car of the train and supplemental tanks 100 connected therewith and located in the several cars, it will be possible to avoid all confusion and labor of attending to the soap supply from beginning to end of long journeys by rail.

By eliminating the individual reservoirs from liquid soap dispensers, and dispensing the soap directly from a hollow bracket as 105

shown herein, an economy of highly valuable space is effected.

Another object is to provide a liquid soap dispenser from which the liquid soap will be discharged positively by the action of a plunger and not by mere gravity as the soap is liable to dry in the discharge tube and thereby prevent the operation provided gravity flow alone is depended upon.

16 The accompanying drawings illustrate the invention.

Figure 1 is a view partly in section, and on a small scale, of a liquid soap dispensing apparatus constructed in accordance with 15 this invention and installed in a sleeping car or hotel lavatory, a fragment of which is shown. Fig. 2 is an enlarged axial section of one of the dispensing devices shown in Fig. 1, the parts being shown in normal 20 closed position. Fig. 3 is a view analogous to Fig. 2, showing the parts in charging position, the piston being pushed in. In this view a modification of the tubular bracket is shown for application where tubing is applied outside a supporting wall. Also the air chamber shown in Fig. 2 is dispensed with. Fig. 4 is a fragmental sectional view analogous to Figs. 2 and 3 showing an intermediate closing position. Fig. 5 30 is a cross section on line x^5 , Fig. 2, looking in the direction of the arrow. Fig. 6 is a cross section on line x^6 , Fig. 2, looking toward the knob. Fig. 7 is a fragmental vertical section of an individual dispensing device provided with an individual reservoir to be filled from the top. Fig. 8 is a perspective view on a reduced scale of a dispenser 35 of the form shown in Fig. 7.

The apparatus in the form shown in Figs. 40 1 and 2, comprises a liquid supply reservoir 1, a tube 2 leading therefrom, nipples 3 leading from said tube, and hollow bracket stems 4 secured to said nipples. Each of 45 said bracket stems 4 is provided with suitable means, such as a flange 6, for securing it to a support or wall 5, by means of screws 7.

The head of the bracket stem 4 is shaped 50 to form a casing or housing 8, having within its walls a main chamber 9 adapted to accommodate the operating or valve mechanism of the apparatus. The main chamber 9 communicates with the hollow bracket stem through the passage 10, thus forming 55 a passage for the liquid from the reservoir 1 to the main chamber 9.

The valve mechanism comprises a valve body 17, provided with a bore 18 in which a valve stem or piston rod 14 moves, and an 60 outlet 19 leading from the wall of said bore; a cylinder 23 extends from the valve body 17 into the main chamber 9. The cylinder 23 is perforated or slotted, and the portion of 65 said cylinder between the outer end of the perforation and the cylinder head or outer

wall constitutes what I call the charge chamber 13. The outer wall of the charge chamber serves also as a valve seat; the perforated end of the cylinder 23 forms part of the main chamber 9.

70 The valve stem 14, which serves also as a piston rod, is provided at its inner end with a valve 15, a piston 11 and an annular recess 16; at its outer end it is provided with a push button 21. A spring 12 is located in 75 the perforated cylinder 23, and bears with one end against the piston 11 and with the other end against the seat 24. The perforated cylinder 23 serves as a guide for the piston when pushed in, also as a housing for 80 the spring. The piston may be provided with a hub 25 to hold the spring in position. A vent 30 may be provided in the seat 24, above the passage 10, to permit the free escape of air from the main chamber into 85 the reservoir through the hollow bracket stem, nipple 3 and tube 2.

The housing 8 may be provided with an air chamber 22, but such chamber is not essential to the proper working of the apparatus.

90 The reservoir 1 is provided with an opening at the top for filling it, and has a cap 33 for closing the opening. It may also be provided with a drain cock 32, and a gage 95 glass 31, the latter for indicating the level of the liquid in the reservoir.

The operation of the device is as follows: The person desiring a supply of liquid soap presses the push button inwardly with the 100 root of the palm of the hand, thus pushing the valve piston out of the charge chamber 13 into the perforated cylinder. The valve piston on its inward stroke, before entering the perforated cylinder, draws air into the 105 charge chamber through the outlet 19 and the recess 16. The moment the outer end of the piston reaches the perforation, the outer end of the valve stem, having the same diameter as that of the bore, closes the outlet 110 19 and thereby forms a valve therefor as shown in Fig. 4. A further advance of the piston inwardly establishes communication between the charge chamber and the main supply of liquid through the perforation. 115 The liquid, by gravity, replaces the air in the charge chamber, the air from said charge chamber escaping into the reservoir and replacing the reduced volume of liquid in the reservoir; thus no air vent is needed 120 in the reservoir to establish equilibrium. When the operator releases the pressure on the push button, the spring forces the valve piston outwardly and when the outer end of the piston reaches the outer end of the perforation, it cuts off communication between the main supply of liquid and the charge chamber, and a further advance of the piston outwardly causes the recessed portion 125 of the valve stem to open communication be-

tween the charge chamber, the valve stem bore and the outlet leading therefrom. The piston actuated by the force of the spring forces the liquid entrapped in the charge chamber out into the palm of the hand of the operator. The portion of the valve stem which is of the same diameter as the valve stem bore is at all times within said bore and prevents any escape of liquid through 10 the outer end of the bore when the apparatus is in operation.

It may be observed that the different parts of the valve mechanism are so constructed and arranged, and the length of the annular 15 recess 16, the depth of the charge chamber 13 and the distance of the outlet 19 from the valve seat are so gaged that at no time, during the inward or outward stroke of the valve piston, can the outlet 19 be in communication with the main source of supply 20 of liquid, hence no liquid can flow out from said main source of supply through said outlet at any of the positions of the valve piston shown in Figs. 2, 3 and 4, nor at any 25 other position in which an operator of the device may hold the valve piston, nor in the event if the spring should in any way fail to properly seat the valve piston on the valve seat.

30 The apparatus, as constructed, can discharge only a measured quantity of liquid, per full stroke of valve piston actuated by force.

When the outlet is normally closed, as 35 shown in Fig. 2, the piston, fitting piston tight in the charge chamber, and the valve seated on its seat by the force of the spring, form a double closure between the main supply of liquid and the outside.

40 In the form shown in Figs. 7 and 8, the operation of the valve mechanism is the same as that shown in the other views. The liquid is supplied from a reservoir 26, preferably of glass, properly secured in a cup 27 45 on top of the main chamber 9; which main chamber is in this case a mere longitudinal extension of the chamber 13. Communication between the interior of the reservoir and the charge chamber 13 is established 50 through the opening in the bottom of the reservoir, and the perforation in the top of the chamber 9, when the valve piston is pushed out of the charge chamber into the main chamber 9. The reservoir is filled 55 through an opening in its top, which open-

ing is normally closed with a removable cap 28.

I claim:—

1. A liquid dispenser having in combination a valve body provided with a charge 60 chamber and with a valve stem bore, an outlet, a piston in said charge chamber that is adapted to normally close communication between said charge chamber and said outlet, and a normally open valve connected 65 with the piston and sliding in said bore for closing the outlet, the construction being such that the space in front of the piston is lessened as the piston advances, and the outlet being separate from the bore and free 70 and unobstructed when the valve is open.

2. A liquid dispenser having in combination a reservoir, a valve body having a charge chamber and a valve stem bore and an outlet leading from the wall of said bore, 75 a piston in said charge chamber that is adapted to normally close communication between said chamber and said outlet, and a normally open valve connected with the piston for closing the outlet, the construction 80 being such that the space in front of the piston is lessened as the piston advances.

3. In a liquid dispenser the combination of a reservoir, a valve body having a charge 85 chamber and a valve stem bore and a passage leading from the wall of said bore, means for supplying liquid from the reservoir to the charge chamber, a valve stem fitting said bore, and a piston on said stem adapted to cut off the supply of liquid to the charge 90 chamber when communication between the charge chamber and the passage from the bore is established, said piston also serving as means for normally closing communication between the charge chamber and the 95 bore; said valve stem being provided with a channel adjacent said piston and communicating with said outlet, the construction being such that the space in front of the piston is lessened as the piston advances, 100 and a spring yieldingly holding such piston in normal position.

In testimony whereof, I have hereunto set my hand at Los Angeles, California, this 21st day of February, 1912.

GABRIEL A. BOBRICK.
